(57) **CLAIM**

The ornamental design for a wheel nut cover, as shown and described.

DESCRIPTION

FIG. 1 is a perspective view of a wheel nut cover showing my new design, shown in its position of use;

FIG. 2 is an enlarged perspective view thereof;

FIG. 3 is an enlarged side view thereof;

FIG. 4 is an enlarged side view thereof, opposite the side of FIG. 3;

FIG. 5 is an enlarged front view thereof;

FIG. 6 is an enlarged top view thereof; and,

FIG. 7 is an enlarged bottom view thereof.

The broken line showing of environment is for illustrative purposes only and forms no part of the claimed design.
